US00D856979S

(12) **United States Design Patent** (10) **Patent No.:** **US D856,979 S**
Seo et al. (45) **Date of Patent:** **** Aug. 20, 2019**

(54) **REMOTE CONTROLLER**

(71) Applicant: **Samsung Electronics Co., Ltd.**, Suwon-si (KR)

JP D1229382 2/2005
KR 30-0724312 1/2014

(Continued)

(72) Inventors: **Yong Seo**, Seoul (KR); **Minki Ham**, Seoul (KR); **Eunha Choi**, Yongin-si (KR)

(73) Assignee: **SAMSUNG ELECTRONICS CO., LTD.**, Suwon-si (KR)

(**) Term: **15 Years**

(21) Appl. No.: **29/658,883**

(22) Filed: **Aug. 3, 2018**

Related U.S. Application Data

(63) Continuation of application No. 29/608,346, filed on Jun. 21, 2017, now Pat. No. Des. 827,613.

(30) **Foreign Application Priority Data**

Dec. 23, 2016 (KR) 30-2016-0062843

(51) **LOC (12) Cl.** **14-03**

(57) **CLAIM**

The ornamental design for a remote controller, as shown and described.

DESCRIPTION

FIG. 1 is a front perspective view of a remote controller showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof, in which a strap is shown in broken lines to illustrate an example environment.

The broken lines in the drawings depict environment and portions of the remote controller that form no part of the claimed design.

1 Claim, 8 Drawing Sheets
